GARMENT SUPPORT

Filed Dec. 9, 1927

UNITED STATES PATENT OFFICE.

WILLIAM H. ROSE, OF JERSEY CITY, NEW JERSEY.

GARMENT SUPPORT.

Application filed December 9, 1927. Serial No. 233,888.

My invention relates to garment supports and refers particularly to devices suitable for supporting a garment during its storage and shipment.

- 5 One of the objects of my invention is a device of such construction that it will support a garment in its original folded position during its handling incident to carriage and shipment.
- 10 Another object of my invention is a device of the character described which will not necessitate the use of boxes or containers during shipment.

Another object of my invention is a device 15 of the character described of such construction that expert packing experience is not necessary in its employment.

Another object of my invention is a device 20 of the character described of such construction that when a number of garments are piled upon each other, access may be obtained to any one of them without disturbing the folding of the others.

The above and other desirable attributes 25 of my device will be evident upon a consideration of this specification and its accompanying drawings.

The usual method of packing a plurality 30 of garments, such as ladies' dresses, for shipment is to fold them and place them one upon the other in a box or container. Unless the shipping container is of exactly the proper size with special reference to the depth, the garment will move during this 35 shipment resulting in the creasing and injuring of the garments.

It is evident, therefore, that a large number 40 of boxes of various sizes must be always in stock in order that the garments may be packed to the best advantage.

Further it is evident that if the garments are packed sufficiently tight to insure non-movement during shipment, such packing will cause the garments to be so tightly 45 pressed upon each other as to cause damage thereto.

It is also evident that the best results 50 can be obtained only by expert packers receiving wages in excess of ordinary labor.

It is further evident that when so packed, the removal of the garments from the packing box will necessitate their re-arrangement for purposes of storing.

55 It is also evident that the removal of any

garment will disarrange the folding and packing of the others.

All of the aforementioned and other objectionable features incident to the packing of garments in boxes are overcome by my invention which presents a means whereby a plurality of garments may be packed for shipment in such condition that they will not be disarranged during shipment handling, that ordinary labor may accomplish 60 this result, that any one of the garments may be obtained without disarranging the folding of the others, that the use of shipping boxes is unnecessary, and that they may be stored, or hung up separately while remaining upon my device.

My device, therefore, is a most effective and economical means for accomplishing the results desirable in the shipment and storage 70 of garments.

In the accompanying drawings illustrating 75 one form of the device of my invention, similar parts are designated by similar numerals.

Figure 1 is a front view of one form of 80 my device with a garment shown in dot-and-dash lines.

Figure 2 is an end elevation of Figure 1.

Figure 3 is a section through the line 3—3 85 of Figure 1.

The particular form of the device of my invention shown in the accompanying drawings comprises a body member 10, composed of a heavy cardboard or other suitable material, attached to the upper portion of 90 which is a double sided shoulder support 11. This shoulder support 11 is formed of one piece of cardboard, bent into a U-shape having an upwardly extended member 11' within which is the upper portion of the body 95 10, the two being fastened together by the staples 12, 12. Each side of the shoulder support 11 is scored along the lines A—A and B—B to allow of the several parts being easily folded over each other, for purposes 100 described later. The shoulder 11 is of such a shape as to conform with the shoulder portion of a garment.

A skirt support 13 is formed of one piece 105 of cardboard bent into a U-shape with the central portion 13' extended, within which is the lower portion of the body 10, the two being fastened together by the staples 14, 14.

While it is not essential that the shoulder 110 support 11 and the skirt support 13 have the

respective shoulders 15 and 16, I prefer this construction, as it allows ample garment space between the body 10 and the shoulder support and the skirt support.

5. The operation of my device is as follows:—

The device is laid upon a table, and a dress 17 is laid thereon. The shoulder support 11 is then folded along the lines A—A and B—B and inserted within the upper portion 18 of the garment and is then extended, thus forming a support for the upper portion of the garment. The skirt support 13 is then placed within the lower portion 20 of the garment.

15. It will thus be noted that the garment rests practically flat and unfolded upon the body member 10 and is maintained in position by the shoulder support 11 and the skirt support 13.

20. It will be further noted that the device may be suspended in a vertical position by means of a nail or hook passed through the opening 21 and that the garment will be maintained in position.

25. The device is then reversed upon the table and a garment similarly positioned upon the exposed side of the device.

A plurality of the thus loaded devices may be placed upon each other, either with or 30 without sheets of cardboard between them, and may then be wrapped in paper preferably with cardboard over the two exposed sides.

It will thus be seen that by means of my 35 device a plurality of garments may be readily packed for shipment and they will be maintained in practically their original positions during shipment, thus preventing the injury resulting from movement incident 40 to the ordinary box packing.

It will be further noted, that my device does away with packing boxes and thus presents a means for materially reducing the space occupied by the packing means in both 45 storage and shipping.

It further obviates the necessity of having a stock of boxes of different depths to accommodate a variety of number of garments.

50. My device thus presents a means for the economic and efficient packing of garments with the prevention of injury to the garments due to the shifting of their positions during shipping and handling.

55. I do not limit myself to the particular size, shape, number, arrangement or material of parts as shown and described as these are given simply as a means for clearly describing the device of my invention.

60. What I claim is:—

1. In a garment carrying device capable of maintaining a garment in an extended position, in combination, a flat body portion, a downwardly extended shoulder support carried by one portion of the body member ca-

pable of insertion within the upper portion of a garment resting upon a face of said body member of the device and an upwardly extended skirt support carried by the opposite portion of said body member capable of insertion within the lower portion of said garment.

2. In a garment carrying device capable of maintaining a garment in an extended position, in combination, a flat body portion, a downwardly extended shoulder support carried by one portion of the body member capable of insertion within the upper portion of a garment resting upon a face of said body member of the device and an upwardly extended skirt support carried by the opposite portion of said body member capable of insertion within the lower portion of said garment said shoulder support and said skirt support being of lesser width than said body member.

3. In a garment carrying device capable of maintaining a garment in an extended position, in combination, a flat body member, a U-shaped shoulder support extending downwardly across both faces of said body member capable of insertion within the upper portions of two garments resting upon the opposite faces of said body member and a U-shaped skirt support extending upwardly across both faces of said body member capable of insertion within the skirt portions of said two garments.

4. In a garment carrying device capable of maintaining a garment in an extended position, in combination, a flat body member, a U-shaped shoulder support extending downwardly across both faces of said body member capable of insertion within the upper portions of two garments resting upon the opposite faces of said body member and a U-shaped skirt support extending upwardly across both faces of said body member capable of insertion within the skirt portions of said two garments, said shoulder supports and said skirt supports being of lesser width than said body member.

5. In a garment carrying device capable of maintaining a garment in an extended position, in combination, a flat body portion, a downwardly extended shoulder support carried by one portion of the body member having vertical parallel scorings therein and capable of insertion within the upper portion of a garment resting upon a face of said body member of the device and an upwardly extended skirt support carried by the opposite portion of said body member capable of insertion within the lower portion of said garment.

6. In a garment carrying device capable of maintaining a garment in an extended position, in combination, a flat body portion, a downwardly extended shoulder support carried by one portion of the body

member having vertical parallel scorings therein and capable of insertion within the upper portion of a garment resting upon a face of said body member of the device and 5 an upwardly extended skirt support carried by the opposite portion of said body member capable of insertion within the lower portion of said garment, said shoulder and said skirt support being of lesser width

10 than said body member.

7. In a garment carrying device capable of maintaining a garment in an extended position, in combination, a flat body member, a **U**-shaped shoulder support extending 15 downwardly across both faces of said body member having vertical parallel scorings therein and capable of insertion within the upper portions of two garments resting upon the opposite faces of said body member 20 and a **U**-shaped skirt support extending upwardly across both faces of said body

member capable of insertion within the skirt portions of said two garments.

8. In a garment carrying device capable of maintaining a garment in an extended position, in combination, a flat body member, a **U**-shaped shoulder support extending downwardly across both faces of said body member having vertical parallel scorings 25 therein and capable of insertion within the upper portions of two garments resting upon the opposite faces of said body member and a **U**-shaped skirt support extending upwardly across both faces of said body member capable of insertion within the skirt 30 portions of said two garments said shoulder supports and said skirt supports being of lesser width than said body member.

Signed at New York city, in the county of New York and State of New York, this 8th day of December, 1927.

WILLIAM H. ROSE.
